ERASER SHIELD

Donald Southwell Richardson, London, England

Application February 7, 1939, Serial No. 255,094
In Great Britain March 9, 1938

5 Claims. (Cl. 120—41)

This invention relates to eraser shields of the kind used by typists in order that an error in one or more letters which have been typed can be erased without mutilating an adjacent letter.

5. More particularly, the invention relates to eraser shields of the type (hereinafter referred to as the type described) consisting of a thin sheet of material having one or more holes or slots which can be placed on the line of writing so that only the letter or letters, which have to be erased, are exposed to view through a hole.

Heretofore, shields of the type described have been rectangular in shape with rounded corners, and these shields have been used not only as eraser shields, but also as advertising devices and, in some cases, as visiting cards. When made of Celluloid, it has been found by experience that the material must not exceed .015" in thickness, otherwise the shields are not flexible enough to bend round the typewriter platen, while if they are less than .010", although they are very satisfactory with regard to flexibility, the Celluloid is so brittle that it very easily breaks, rendering the shields useless after a short time. Further, the arrangement of the slots has heretofore been quite arbitrary, and the slots in a shield have been designed, as to their width, length and shape, with reference to only one particular letter spacing on a typewriting machine with which the shield 10 was intended to be used. As the letter spacing on typewriting machines varies from 12 to the 1" to 8 to the 1", it will be appreciated that a shield designed for use with one spacing may not be well adapted to be used with a machine of a different spacing.

An important object of the present invention is to provide an improved construction of eraser shield of the type described which shall be more convenient in use than those known heretofore, and in which the slots are arranged in a predetermined manner with reference to the centre of the shield.

According to the invention there is provided an eraser shield of the type described, wherein a row of slots is arranged circularly or in a curved path around the central portion of the shield, which slots are situated nearer to the periphery than to the center of the shield and each lies at an acute angle on a line radial to the central portion of the shield, so that rotation of the shield about its central portion will place the slots successively in their correct position of use.

Two or more of the slots may lie respectively at successively greater or lesser distances from the center of the shield.

Preferably, the shield having a plurality of slots is so constructed that when it is rotated about its centre, each slot will lie in turn at its correct position of use for a right-handed typist, or if the shield is reversed, for a left-handed typist.

The slots may be so arranged in spaced relation around the centre of the shield that the angular distances between them are substantially equal one to another.

The shield may have a circular periphery.

Alternatively, the shield may have a polygonal or substantially polygonal periphery of regular or irregular shape, but having more than four sides.

One embodiment of the invention is diagrammatically illustrated by way of example in the accompanying drawing, wherein:

Figure 1 is a plan view showing one form of eraser shield provided with slots according to the invention, and

Figures 2 to 7 illustrate the slots drawn to a larger scale than that of Figure 1.

Referring to the drawing, the shield 10 made of thin sheet material, preferably has an overall 25 diameter of about 3". It has in it eight slots numbered 11 to 18 lying respectively each on one of eight radii which will be referred to by, and are marked with the points of the compass W, SW, S, SE, E, NE, N, NW. There is no aperture 30 at the centre of the shield. Some of the slots differ in size from that of others, and some lie nearer the periphery of the shield than the others. The slots 11, 12, 13, 15 and 16 lie centrally on the radii W, SW, S, E and NE, respectively, while the centres of the three slots 14, 17 and 18 are displaced angularly a few degrees anti-clockwise from the radii SE, N and NW, respectively, and lie respectively on radii ESE, NW, and WNW.

A numeral or other index, printed or otherwise applied to the shield, is allotted to each slot, which numerals run consecutively from 1 to 8, and are so positioned in relation to the slots that when the numeral allotted to a slot is placed vertically, that slot is in its position of use. Each numeral may be provided with a mark, such as an arrow or a diamond surrounding it, for facilitating positioning it vertically by rotating the shield. In the position of the shield shown in 50 Figure 1 the numeral 4 is vertical, and the slot 14 is vertical in its position of use. Similarly, when the numerals 1, 2, 3, 5 and 6 are placed vertically their slots will be vertical in the position of use, while, when the numerals 7 and 8 55

are vertical, their slots 17 and 18, respectively, will be horizontal in the position of use.

The major and minor axis of each slot make an angle less than 90° with the respective radius bisecting the slot. Preferably, the angle at which the major axis of a slot lies on its radius is between 40° and 50° when the slot is used either vertically or horizontally for erasing letters on lines above the bottom of the sheet, but for erasing letters in a line at the bottom of the sheet, the corresponding angle of the vertical slot may be reduced to 20° to 25°. As indicated in Figure 1, the angles which the major axes of the slot make with the radii passing through their centres are as follows:

	Degrees
Slots 11, 12 and 15	45
Slots 13 and 16	22.5
Slot 14	48
Slot 17	41.5
Slot 18	41

When the slots are inclined at the angles just mentioned, it is found that the centre of the slot in the operating position for vertical erasing is between $\frac{1}{4}$ " to $\frac{5}{8}$ " from the bottom of the shield and $\frac{11}{16}$ " in the case of a horizontal slot, when the shield has an overall diameter of 3". When in use, the shield is taken up by the operator and rotated about its central portion, and the appropriate slot is brought into its correct operating position, whereupon the shield is placed against the paper for the erasing operation. If the slots are arranged sloping in the direction for use by a right-handed typist, when the shield is reversed, it will be found that the slots can be used by a left-handed typist.

The slots lying on the various radii are shown at the following distances from the centre of the shield:

40. Radii W, SW, S, E and NE at $1\frac{7}{32}$ "
 Radius WNW at $1\frac{1}{32}$ "
 Radius NWN at $3\frac{1}{32}$ "
 Radius ESE at $1\frac{1}{8}$ "

45. It will be seen that the three slots 17, 18 and 11 lie on their radii respectively successively greater distances from the centre of the shield when considered in counter-clockwise direction, and at successively lesser distances therefrom when considered in a clockwise direction.

As shown in Figures 2 to 7 the dimensions in inches of the various slots on the 3" shield shown in Figure 1 are as follows:

55	No. of slot	Major axis	Minor axis	Length of radius of curvature of side of slot	Length of radius of curvature of end of slot
60	11	$\frac{5}{16}$ "	$\frac{1}{16}$ "	$\frac{3}{32}$ "	$\frac{1}{32}$ "
	12	$\frac{3}{32}$ "	$\frac{3}{8}$ "	$\frac{3}{64}$ "	$\frac{1}{32}$ "
	13, 15 and 16	$\frac{1}{32}$ "	$\frac{9}{64}$ "	$\frac{5}{32}$ "	$\frac{1}{32}$ "
	14	$\frac{3}{8}$ "	$\frac{9}{64}$ "	$\frac{3}{64}$ "	$\frac{1}{32}$ "
	17	$\frac{1}{16}$ "	$\frac{7}{32}$ "	$1\frac{1}{16}$ "	$\frac{3}{32}$ "
	18	$1\frac{1}{32}$ "	$1\frac{9}{64}$ "	$3\frac{1}{128}$ "	$\frac{1}{32}$ "

65. These dimensions are given by way of example only, and it is to be understood that the oval slots for horizontal use may vary from $\frac{11}{16}$ " to $\frac{5}{8}$ " in length and from $\frac{1}{8}$ " to $\frac{7}{32}$ " in width.
 70. Slots for vertical use may vary from $\frac{3}{32}$ " to $\frac{5}{8}$ " in length and $\frac{1}{8}$ " to $\frac{9}{64}$ " in width.

When the shield is polygonal, its sides may be straight or curved and of any convenient number more than four. The shield illustrated may 75 be regarded as an octagonal figure, whereof the

angles and sides are rounded or curved. The use of a polygon rather than a circle is convenient in that if flat sides are used, one side for every slot, whenever one of the flat sides is held parallel to the axis of a platen, a slot will be situated in its correct position of use. In the example illustrated, when the middle curved portion of a side at the bottom of Figure 1 is situated in the N-S direction, a slot 14 to the right-hand thereof will be situated in its correct position of use. 10

The shield may be made of any convenient sheet material, preferably vulcanised fibre; other materials, such as presspahn, leatheroid, press board, Celluloid and metal may, however, be used. The shield, particularly when made of 15 vulcanised fibre, may be provided with a protective coating, e. g., cellulose lacquer, varnish, casein, methyl cellulose, or a water-soluble resin; in some cases, the coating may consist of a lining of regenerated cellulose. 20

Various modifications may be made in the details of form and arrangement of the slots described above. For example, the angular spacing of the radii on which the centres of the slots are situated may vary a few degrees from the positions indicated on the drawing. Similarly, the size and shapes of the various slots may be modified slightly. 25

I claim:

1. An eraser shield of the character described, 30 consisting of a thin sheet of material having a polygonal periphery with more than four sides and having a plurality of erasure slots of elongated formation arranged in spaced relation in a substantially circular, endless row that surrounds the central portion of the shield and lies nearer to its periphery than to its center, each of which slots lies at an acute angle on a line that is radial to the central portion of the shield and substantially bisects one of the sides of the 35 polygon and each slot is disposed at an acute angle to the respective radial line on which it lies.

2. An eraser shield of the character described, 40 consisting of a thin sheet of material having a plurality of erasure slots of elongated formation arranged in spaced relation in a substantially circular, endless row that surrounds the central portion of the shield and lies nearer to the periphery than to the center of the shield, each 45 of which slots is disposed at an acute angle to the line radial to the central portion of the shield on which it is situated, and a plurality of indices that are allotted each to one of the slots, and are so positioned that when they are 50 placed vertically their allotted slots will be in the position of use.

3. An eraser shield of the character described, 55 consisting of a thin, substantially circular sheet of material having a plurality of oval erasure 60 slots arranged in substantially equal spaced relation in a substantially circular, endless row that surrounds the center of the shield and lies nearer to its periphery than to the center, each of which slots is disposed with the direction of 65 its length at an acute angle on the line that is radial to the center of the shield on which it lies, and a plurality of indices that are allotted each to one of the slots, and are so positioned that when they are placed vertically, their allotted slots will be in the position of use. 70

4. An eraser shield of the character described, 75 consisting of a thin substantially circular sheet of material having a plurality of erasure slots all of elongated formation and all arranged in spaced 80

relation in a substantially circular, endless row that surrounds the central portion of the shield and lies nearer to the periphery than to the center of the shield, each of which slots is disposed at an acute angle of between 20° and 50° to the line radial to the central portion of the shield on which it is situated.

5. An eraser shield of the character described, consisting of a thin sheet of material having a plurality of erasure slots all of elongated formation and all arranged in spaced relation in an

endless curved row that surrounds the central portion of the shield and lies nearer to the periphery than to the center of the shield, each of which slots is disposed at an acute angle to the line radial to the central portion of the shield on which it is situated, at least two of which slots, next adjacent one to another, lie respectively at successively greater distance from the center of the shield.
